UNITED STATES PATENT OFFICE.

IRA M. CLARKE, OF NEW MARTINSVILLE, WEST VIRGINIA.

DESIGN FOR A PUFF AND ROUGE BOX.

Application filed February 3, 1926. Serial No. 16,382. Term of patent 3½ years.

To all whom it may concern:

Be it known that I, IRA M. CLARKE, a citizen of the United States, residing at New Martinsville, in the county of Wetzel, State of West Virginia, have invented a new, original, and ornamental Design for Puff and Rouge Boxes, of which the following is a specification, reference being had to the accompanying drawing, forming part thereof.

The figure is a side elevation of my ornamental design.

I claim:—

The ornamental design for a puff and rouge box, as shown.

IRA M. CLARKE.
